PAGE 2

Fig. 2.

Fig. 3.

Fig. 4.

Fig. 5.

FIG. 1 is a top plan view of a lavatory showing my new design.

FIG. 2 is a front elevational view thereof.

FIG. 3 is a rear elevational view thereof.

FIG. 4 is a side elevational view thereof.

FIG. 5 is a cross-sectional view taken on line 5-5 of FIG. 2.

The characteristic feature of my design resides in the graining striations radiating from the drain outlet of the lavatory. As they extend to the front of the bowl they split and spread out in opposite directions to either side forming symmetrical spirals. The graining striations which extend to the back and to either side from the drain outlet do not have any spirals.

I claim:

The ornamental design for a lavatory or similar article, as shown and described.
